UNITED STATES PATENT OFFICE.

HARMON JOHN MILLER, OF DEFIANCE, OHIO.

DEVICE FOR LINING RAILWAY TRACKS.

Application filed January 19, 1926. Serial No. 82,257.

This invention relates to devices for lining railway tracks.

The object is to provide a strong and durable device of simple construction to be used in railroad construction and repair or maintenance work for the purpose of lining up rails or sections of track which require horizontal or vertical adjustment, said operations, which are very difficult, requiring many workmen, being more easily and quickly accomplished with the use of the present device and with a minimum amount of labor.

Another object is to provide a lining device for railroad tracks which may be used in conjunction with any of the well known and powerful jacks used in connection with railroad work, whereby the rail or rails to be moved and adjusted may be raised from the ground or ballast sufficiently to permit same to be free and readily shifted in the desired lateral direction, and then to be tamped or chocked in the usual manner at the proper elevation and in proper longitudinal alignment with the adjoining portions of the track, the invention being adapted to be placed in position at any place along the rail so as to properly engage the same for the purpose.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a side elevation of the improved device shown in connection with a track jack and engaged with a railroad rail.

Figure 2 is a perspective view of the invention.

Figure 3 is a detail horizontal section through a portion of the device.

The invention comprises a base member 1

in the form a relatively heavy metal plate 55 of rectangular form having a width somewhat less than the distance between railroad ties and a length substantially three times as great as the width thereof, said plate being sufficiently thick as to prevent 60 bending when under the great strain of lifting the rails when in use.

Adjacent to one end the base plate 1 is provided with two pairs of upstanding, opposed posts 2 and 3 respectively, the pairs being 65 arranged in spaced, parallel relation to each other and equidistant from the longitudinal center line of the base plate. The end posts 2 are spaced from the adjacent end of the base plate, and the several posts are rigidly 70 mounted on the base member in any suitable manner and are provided near their upper ends, with apertures aligned longitudinally of the base member, for the reception of bolts 4 having suitable heads and nuts bearing 75 against the faces of the posts to rigidly hold the bolts in position, and to permit the removal of the bolts when desired by simply turning off the nuts, for a purpose to be described.

A metal bar 5, commonly known as a "crowding bar", and formed preferably of heavy wrought iron or steel is mounted longitudinally of the base plate with one end located between the pairs of posts 2 and 3, 85 said end being rounded, as shown at 6, and adapted to bear upon the base plate between the pairs of posts and to act as a fulcrum for the crowding bar when the opposite end of the latter is elevated.

A transversely disposed metal pin is mounted in a suitable aperture formed in the rounded end of the bar and concentrically to the same, said pin extending outwardly an equal distance on either side of the bar 5 to 95 constitute trunnions 7 which project between the posts 2 and 3 of each pair respectively, and form a loose connection between the crowding bar and the base member and prevent separation of the two parts. The 100 thickness of the bar 5 is somewhat less than the distance between the pairs of posts and considerable lateral play is provided for the said bar, and the diameter of the trunnions is considerably less than the space between 105 the posts 2 and 3 of each pair for the same purpose, so that the rounded, nose end of the crowding bar may freely rock on the base

member without any danger of breakage of the parts were the bar to be directly pivoted upon the trunnions when under the great weight of the rail or rails. In addition, the lateral freedom of the bar allowed by this manner of mounting the same, permits of its ready adjustment to the edge of the flange of the rail when lifting, in the event the base member is not placed exactly 10 square relative to said rail.

The bar 5 is arcuately curved throughout its length with the concave surface uppermost and, adjacent to the free end thereof, is provided with a horizontal, transverse 15 aperture 8 in which is engaged a stout wrought iron or steel link 9, closed at each end and adapted to freely swivel in the said aperture 8.

The link 9 is adapted to be placed over 20 the lifting toe 10 of an ordinary track jack 11, which may be of any of the well known constructions in common use on railroads, the same having the usual operating handle 12 adapted to be rocked up and down and 25 having means for actuating the vertically movable rack bar 13 to which the toe 10 is connected, and having suitable means for engaging the bar 13 to hold the same at the desired elevation.

The base plate 1 is provided with a transverse cleat 14 secured to the upper face thereof in any desired manner and located at 30 an intermediate point between its ends, said cleat serving as a rest for the crowding bar 5 to hold the link end elevated when not in use, and at the same time to serve as a stop for the extended base 15 which is integrally 35 joined to the standard 16 of the jack 11 so as to prevent any inward slipping movement of the jack upon the base member 1 when under load.

The upper concave face of the crowding bar 5 has its side edges bevelled, as shown 40 at 17, so as to reduce the friction when engaged with the edge of the flange 18 of the rail 19, as it is desired that the latter slip along the bar 5 as the lifting operation proceeds.

In operation, the base plate is placed upon 50 the ground or ballast between the ties 20 of the track and said base, if desired, may be mounted on a stout piece of wood or other material, holes 1^a being provided in the base for that purpose. The jack 11 is then placed 55 thereon with the foot or base 15 abutting the transverse cleat 14, and the bar 5 is elevated so that the link 9 may pass over the toe 10 of the lifting jack. By proper operation of the handle 12 the bar 5 is caused 60 to rise and engage the flange of the rail, and by reason of the curvature thereof said rail is raised sufficiently to be free of the ground or ballast and the same will slide along the edge of the bar 5 in a lateral direction to 65 shift said rail, together with the ties and

the other rail to the proper position to align with the rest of the track.

From the foregoing it will be seen that a simple, strong and durable device has been provided for use in aligning tracks when the 70 same have become disaligned from washouts, wrecks, or from other causes, or for use when constructing roads, the device being easily and quickly placed in operative position to lift and to move tracks and readily 75 connected with any form of track jack the power from which is utilized through the arcuate crowding bar to affect the track in the desired manner; and it will be further seen that the strain imparted to the said 80 bar is placed directly upon the base plate so that the danger of breaking or deranging the few simple parts of the device is reduced to a minimum, and by reason of the trunnions 7, posts 2 and 3, and the bolts 4, the 85 bar is permitted to so function and yet is retained at all times, upon the base member and may only be separated therefrom by the removal of said bolts.

What is claimed is:—

1. A track lining device comprising a base adapted to rest on the ground between the ties, a crowding bar located above the base and adapted to fulcrum at one end directly upon the base, outstanding trunnions carried at the fulcrum end of the bar, pairs of upstanding, spaced posts mounted on the base at either side of the said fulcrum end and adapted to abut the trunnions to limit the longitudinal movement of the bar upon the base, removable bolts joining the upper ends of each pair of posts to prevent separation of the bar and base, and means carried by the free end of the bar for direct connection with a track jack.

2. A track lining device comprising a flat, metal base of rectangular form, spaced pairs of upright posts rigidly mounted on the base adjacent to one end of the same, the posts of each pair being spaced apart longitudinally of the base to constitute spaced abutments, a crowding bar arranged longitudinally of the base and having outstanding trunnions at one end adapted to project between the abutments, said end of the bar being rounded to fulcrum directly on the base when the other end of the bar is lifted, and a link pivoted to the outer end of the bar to receive the toe of a track jack.

3. A track lining device comprising a flat, metal base of rectangular form, spaced pairs of upright posts rigidly mounted on the base adjacent to one end of the same, the posts of each pair being spaced apart longitudinally of the base to constitute spaced abutments, a crowding bar arranged longitudinally of the base and having outstanding trunnions at one end adapted to project between the abutments, said end of the bar being rounded to fulcrum directly on the base 120

when the other end of the bar is lifted, said bar being curved throughout its length with its concave side uppermost and having the edges of said upper side beveled, a swivelled link carried by the free end of the crowding bar for connection with a track jack and a transverse cleat mounted intermediately on

the base to normally hold the bar elevated and to act as a stop for the base of said jack.

In testimony, that I claim the foregoing 10 as my own, I have hereto affixed my signature.

HARMON JOHN MILLER.
